UNITED STATES PATENT OFFICE.

MARQUIS F. DICKINSON, JR., OF COHASSET, AND KATE B. WORMWOOD AND LUTHER H. WORMWOOD, OF NEWTON, MASSACHUSETTS, EXECUTORS OF SAMUEL P. WORMWOOD, DECEASED.

DESIGN FOR A TOE-CALK.

SPECIFICATION forming part of Design No. 29,794, dated December 13, 1898.

Application filed November 18, 1898. Serial No. 696,823. Term of patent 14 years.

To all whom it may concern:

Be it known that SAMUEL P. WORMWOOD, deceased, late of Newton, in the county of Middlesex, Commonwealth of Massachusetts, 5 did invent a new and original Design for a Toe-Calk, of which the following description, in connection with the accompanying drawings, is a full, clear, and exact specification, such as will enable those skilled in the art to 10 which it relates to make, construct, and use the same.

Referring to the accompanying drawings, Figure 1 is a perspective view from one end, and Fig. 2 is a perspective view from the other 15 end, of the design for a toe-calk.

As shown in the drawings, the leading and material features of the design consist in a rectangular parallelepipedal body provided

on one side with a tapering projection displaced from the longitudinal center line of the 20 said side and set back from the ends thereof.

Having thus described the invention, what is claimed as new, and desired to be secured by Letters Patent, is—

The design for a toe-calk, substantially as 25 shown and described.

In witness whereof we affix our signatures in presence of two witnesses.

MARQUIS F. DICKINSON, JR.,
KATE B. WORMWOOD,
LUTHER H. WORMWOOD,
Executors of Samuel P. Wormwood, deceased.
